J. P. WEIS.

WORK HOLDING FOOT MECHANISM.
APPLICATION FILED JAN. 2, 1919.

1,419,087.

Patented June 6, 1922.

Inventor

By his Attorney John P. Weis.
Edward S. Beadle

UNITED STATES PATENT OFFICE.

JOHN PETER WEIS, OF NYACK, NEW YORK, ASSIGNOR OF ONE-HALF TO METROPOLITAN SEWING MACHINE CORPORATION, OF DOVER, DELAWARE, A CORPORATION OF DELAWARE.

WORK-HOLDING-FOOT MECHANISM.

1,419,087.

Specification of Letters Patent. Patented June 6, 1922.

Original application filed October 16, 1914, Serial No. 867,005. Divided and this application filed January 2, 1919. Serial No. 269,273.

To all whom it may concern:

Be it known that I, JOHN PETER WEIS, a citizen of the United States, residing at Nyack, in the county of Rockland and State 5 of New York, have invented certain new and useful Improvements in Work-Holding-Foot Mechanisms, of which the following is a specification.

This invention is an improvement in work-holding foot construction for sewing machines. The object of the invention is to secure a simple and convenient work-holding foot which shall automatically adjust itself to variations in thickness of goods fed to 15 the stitch-forming instrumentalities while the needle is operating at high speed, and be operable to glide over the goods in a traveling sewing machine.

In the accompanying drawings forming 20 part hereof,

Fig. 1 is a front elevational perspective of the front end portions of the upper and under arm of a sewing machine head embodying this invention and showing the 25 stitch-forming instrumentalities, the work-holding foot being omitted for greater clearness.

Fig. 2 is a front elevation of what is shown in Fig. 1, with the work-holding 30 foot in place.

Fig. 3 is a perspective view of the needle-bar-actuating crank removed.

Fig. 4 is a perspective view of the needle-holder guide detached.

Fig. 5 shows the needle holder in plan 35 and side elevation.

Fig. 6 is a detailed view partially in section at line 6—6 to Fig. 5 of the needle holder and co-operating parts.

This application is a division of my pending 40 application Serial No. 867,005, filed October 16, 1914.

Referring to the drawings, A represents the upper arm and A' the under arm of a 45 sewing machine head. The under arm carries an oscillating looper L on a looper shaft M. The upper arm carries a needle-drive shaft D on the front end of which is a crank 1 having on its rearward side about midway 50 between its ends a right-angular tubular

socket 2 that opens through the front wall of the crank. The latter is made approximately as the segment of a circle and is wider at one end in order to serve as a counterbalancing weight than it is at its narrower end from the front side of which a crank pin 3 projects. The crank socket is secured on the front end of the drive shaft D by pins x. On crank pin 3 of this side-weighted crank there is pivoted the upper end of a dependent pitman 4 the bottom end of which is pivoted at 5 to a sliding needle holder 6 holding the shank of the needle B. In the under end portion of the upper arm A there is socketed a dependent approximately L-shaped needle-holder guide which is generally indicated by G (Fig. 4) having an approximately half-round shank 7; at the foot of the shank a laterally projecting shoulder 8 from the outer end portion of 60 which there projects downwardly a cross-sectionally L-shaped bar 9 to the free edge of the flange 10 of which there is fixed a detachable cover-plate 11 by means of screws 12. By this construction a guideway 65 13 is formed for one end of the needle holder. Shank 7 is provided with a dependent cross-sectionally round needle-holder guide pin 14 that is parallel to and opposite the lengthwise opening of the guideway 13. 70

Crank 1 and crank pin 3 are formed with a lubricant duct 15 and the guide pin 14 is formed from its upper end which is flush with the upper end of the shank 7 with a 75 lengthwise-extending lubricant duct 16 that has radial wall openings 17 serving as lubricant ducts.

That portion of the guide G which has the lengthwise-extending guideway 13 is mounted inwardly towards the trunk T of the head, the guide pin 14 being intermediate said portion of the guide G and the needle. The needle guide has a vertical bore 18 slideable on the guide pin 14 and an integral 85 guide wing 19 that slides in the vertical guideway 13. Thus the needle holder is kept from oscillation in a horizontal plane during its vertical reciprocations. At that end of the needle holder which is opposite 90

the vertical bore 18 and guide wing 19 the needle holder is provided with a vertical bore 20 for reception of the needle shank. Between the bores 18 and 20 the needle holder is provided with a side recess 21 so that the bore 18 and the guide wing 19 are in one fork arm and the needle-hole bore 20 in another fork arm of the needle holder which thus straddles the bottom end of pitman 4, such bottom end playing in the recess 21 which is spanned by the pivot pin 5 by means of which the bottom end of the pitman and the needle holder are loosely connected together. The needle holder has a horizontally-extending bore 5^a for the pintle pin 5; and has a horizontal bore 22 throughout its length, at the front side of the web 22^a. The bore 22 constitutes a thread passage. The inward end of the recess 21 intersects this thread passage so that the thread-nipper spring 23 may pass through the inward end portion of the recess 21 between the foot of the pitman and the thread or threads in the thread passage 22 to hold the needle thread whenever and as may be required.

The work-holding foot construction comprises a dependent bracket having a shank 24 that is secured by a screw 25 to the front end of the upper arm A, the shank 24 terminating in an angular outwardly-projecting foot 25^a to the lower end of which by a pivot-screw 26 there is pivoted a work-holding-foot carrier 27 that extends over the throat plate 28^a. The outward end of the work-holding-foot carrier is bent upwardly and inwardly at 28 over the upper side of the angular foot 25^a. The free end of the bend at 28 is provided with an adjusting screw 29 the inward end of which impinges on the upper wall of the foot 25^a. A suitable spring 30 is interposed between the carrier 27 and the under side of the foot 25^a. The spring tends to push the work-holding foot 31 carried by its free end over the throat-plate downwardly and by adjustments of the screw 29 the work-holding foot 31 may be adjusted upwardly in relation to the throat plate 28^a. The front end of the work-holding foot is upturned at 32 easily to glide over goods held down by it by the pressure of the spring 30. This spring pressure on the work-holding foot that glides over the goods when and if the sewing-machine head is bodily moved during stitch-forming operations, is very useful whenever there are variations in the thickness of the goods, as for example in certain ribbed goods during the sewing of which the foot will be lifted automatically against the resistance of the spring 30. The foot 31 has on its upper side back of its needle hole an upstanding wall 33 adjacent the back side of the needle hole and forming a lateral abutment for the needle when in the goods, and the feed of

the goods pulls the needle laterally towards the wall. This is useful in diminishing needle breakage and skipping of stitches.

Emphasis is laid on the location of the pivotal connection at 26 of the pivoted end of the work foot carrier. It is as closely adjacent the upper level of the throat plate as is consistent with the travel of goods across the throat plate 28^a, a goods way Y being formed between the throat plate and the under side of the work-foot carrier 21. By reason of such location, the abutment wall 33 moves practically vertically during the automatic or mechanical adjustments of the work-holding foot. It will be observed in the present case that there is no feed dog or means through the work plate for cooperation with the foot and needle. The foot has only negligible pressure on the goods except at ribs or seams, the carrier 27 being set so that the goods travel over the work plate in very gentle contact with the foot which is movable between the work plate and the under end of the dependent guide G.

The bracket shank 24 while adjustable endwise to vary the working position of the work holding foot above the throat plate, is fixed when in adjusted position. This stationary bracket constitutes the holder or carrier of the work holding foot which while movable on the lower end of the bracket has no reciprocating movement in cooperation with a feed dog, as is the case in most sewing machines. There is no feeding device in the sewing machine head herein shown; and in machines in which my present invention has been incorporated, the feed of the goods has been effected by feed rolls spaced apart from the sewing machine head. If the work holding foot herein described were comparable to the ordinary pressure foot of the usual sewing machine, its bracket shank 24 would have to be endwise movable in order to obtain the rise and fall or reciprocation of the foot synchronously with the movements of a feed dog and relatively to the throat plate.

What I claim is,—

In a sewing machine, the combination with a throat plate and upper and under stitch-forming instrumentalities of a dependent bracket attachable to the machine head and having an angular under end for holding a work holding foot in operative position between the throat plate and the upper stitch-forming instrumentality; a work holding foot pivotally connected to the under end of the bracket and extending from its pivotal connection over the throat plate, at an angle to the angular under end of the bracket; a spring interposed between the angular under end portion of the bracket and the work holding foot, the spring functioning to hold the foot against the upper surface of goods between the throat plate and upper stitch forming instrumentality; and

means for holding the foot in an adjusted position relatively to the throat plate and in which position the spring is ineffective to

move the foot into a lower position towards the goods while the foot is upwardly movable against the tension of the spring to permit goods to be fed freely between the throat

plate and the foot and to prevent the spring from effecting a clamping pressure on the goods.

10

In testimony whereof I have hereunto set my hand this 27th day of December, 1918.

JOHN PETER WEIS.
